Primary Examiner — Mitchell Siegel(74) *Attorney, Agent, or Firm* — Banner & Witcoff, Ltd.(57) **CLAIM**

The ornamental design for a golf club head, as shown and described.

DESCRIPTION

FIG. 1 is a first perspective view of a golf club head showing our new design;

FIG. 2 is a bottom view thereof; and,

FIG. 3 is a second perspective view thereof.

The broken lines showing the remainder of the golf club head are for environmental purposes only and form no part of the claimed design.

1 Claim, 3 Drawing Sheets(56)
